UNITED STATES PATENT OFFICE.

STANLEY CZAPEK, OF DETROIT, MICHIGAN, ASSIGNOR TO RADIANT SPECIALTY CO.,
A CORPORATION OF MICHIGAN.

DESIGN FOR A LIGHTING FIXTURE.

Application filed November 20, 1925. Serial No. 15,482. Term of patent 3½ years.

To whom it may concern:

Be it known that I, STANLEY CZAPEK, a citizen of the United States, residing at Detroit, in the county of Wayne and State of Michigan, have invented a new, original, and ornamental Design for a Lighting Fixture, of which the following is a specification, reference being had to the accompanying drawing, forming a part thereof, and in which,

Fig. 1 is a side elevational view of the invention.

Fig. 2 is a bottom plan view of the invention, only part being completed, the remaining portion being but a repetition of the completed portion.

What I claim is:

The ornamental design for a lighting fixture, as shown.

STANLEY CZAPEK.
